UNITED STATES PATENT OFFICE.

GEORGE F. ALBRECHT, OF WOONSOCKET, RHODE ISLAND, ASSIGNOR TO WOONSOCKET MACHINE & PRESS CO., INC., OF WOONSOCKET, RHODE ISLAND, A CORPORATION OF RHODE ISLAND.

CAP BAR FOR ROVING AND SPINNING FRAMES, ETC.

Application filed May 10, 1922. Serial No. 559,699.

To all whom it may concern:

Be it known that I, GEORGE F. ALBRECHT, a citizen of the United States, residing at Woonsocket, in the county of Providence, 5 State of Rhode Island, have invented a certain new and useful Improvement in Cap Bars for Roving and Spinning Frames, Etc., of which the following is a specification, reference being had therein to the accompanying drawings.

The invention relates to the cap-bar devices of roving and spinning machines, and the like, and more particularly to the so-called nebs which are mounted upon the 15 cap-bar fingers of such devices, and used for keeping the top rolls of a set of drawing rolls in proper working relations with the bottom rolls.

The invention comprises nebs of novel and 20 improved construction made of sheet metal stamped and pressed to shape, and means for fixing the same in the desired adjusted positions upon the cap-bar fingers.

The invention is illustrated in the drawings, in which,—

Fig. 1 is a view of the roller-stand of a roving frame having nebs embodying the invention mounted upon the cap-bar fingers.

Fig. 2 is a side elevation of one of the 30 nebs for the middle or back top rolls, shown separately.

Fig. 3 is a front elevation thereof.

Fig. 4 is a plan view thereof.

Fig. 5 is a view in vertical section on line 35 5, 5, of Fig. 1.

Fig. 6 is a side elevation of one of the nebs for the front top rolls.

Fig. 7 is a front elevation thereof.

Fig. 8 is a plan thereof.

40 Figs. 9 and 10 show one of the nuts employed in connection with the nebs.

In the drawings, a supporting stand is indicated at 21, and at 22, 22, 22, are indicated roll-supports provided with bearings for the 45 journals of the bottom rolls 23, 23, 23. In usual practice, the supports 22, 22, 22, are adjustable in the direction from front to rear in the machine in which the parts are employed, for the purpose of varying the 50 positions of the rolls 23, 23, 23, and the spacing of the rolls apart from one another. One spacing of the said rolls is represented in full lines in Fig. 1 of the drawings. An

adjustment of the back roll into a more rearward position than that shown by the full 55 lines is represented in dotted lines in the said view. The top rolls are indicated at 24, 24, 24.

A well-known form of cap-bar finger is shown at 25 in Fig. 1, it being shaped in 60 cross-section like a cylinder with its upper side slabbed-off and flat longitudinally. Nebs embodying the invention are shown mounted upon the said finger, which is attached to a swinging holder 26 mounted 65 upon a rod 27 which is supported by stands 28 at the rear of the roll-stand. In usual practice, the rod 27 is capable of turning in its bearings in the stands 28, so as to enable the cap-fingers to be swung upward 70 from the working position indicated in Fig. 1, into an inclined elevated position, and to be returned subsequently into the said working position.

In practice, the top-rolls 24, 24, 24, are 75 maintained in proper working relations with the bottom rolls 23, 23, 23, with which they respectively coact, by means of the nebs, which are applied thereto. Ordinarily heretofore such nebs have been constituted of 80 small metal blocks that are bored to fit upon the cap-bar finger 25, the said blocks having lateral portions or ends formed with lateral grooves to receive the end-journals, (indicated by dotted circles in Fig. 1, and 85 also indicated by dotted lines in Fig. 5) of the top-rolls 24, 24, 24. Both of the lateral portions or ends of a neb-block are grooved vertically, as just indicated, in order that one neb may serve to guide and control the 90 proximate-end-journals of two adjoining top rolls.

Nebs made of solid blocks of metal, machined to shape as heretofore usual, involve 95 considerable skilled labor in their production, and are expensive. They frequently are untrue in form. They have, therefore, certain drawbacks and disadvantages which the present invention obviates.

Nebs constructed according to the present 100 invention are made of sheet metal, each of a single piece constituted by a blank stamped or punched from such material and bent by pressure into the required shape of neb. Each neb is formed with a top 105 plate 1 having a central hole 2; also with

front and rear transversely extending vertical walls 3, 3, parallel with each other, having intermediately located holes 4, 4, registering with each other, and also having lateral extensions or wings as indicated in Figs. 3, 4, 5, 7 and 8; and also with side-tangs 5, 5, extending down between the opposite pairs of lateral extensions or wings of the front and rear walls 3, 3 from the opposite sides of the top plate 1. The holes 4, 4, in the said walls are shaped and proportioned to receive within them a cap-bar finger 25; so as to enable the neb to be slipped upon such finger. The distance 15 from the under side of plate 1 down to the said holes is sufficient to accommodate the thickness of a nut 6 interposed between said top plate and the top of the cap-bar finger, and occupying the space enclosed by the front and rear walls 3, 3, and the opposite side-tangs 5, 5. The said nut is one element of the means for fixing the neb in the desired adjusted position in the length of the finger. The other element of the said 25 means is a screw 7, the head of which is located above the plate 1 while the stem thereof extends down through central hole 2 of said plate and through the nut 6, with its lower end resting upon the flat top of the 30 cap-bar finger 25.

After a neb has been slipped into place upon a cap-bar finger 25 with the corresponding nut 6 and screw 7 in proper assembled relation therewith; and also, with 35 the said screw entered into the said nut, the neb is fixedly secured at the desired point in the length of the finger 25 by turning down the screw 7 to cause its tip to bear against the top of the finger 25. The turning 40 of the screw also causes the nut 6 to work upwardly upon the threaded stem of the screw so that the nut by pressing upwardly against the underside of the top plate 1 of the neb raises the neb in its entirety, thereby causing the bottoms of the 45 holes 4, 4, in the vertical walls 3, 3, of the neb to take bearing against the under side of the finger. Through the engagement of the top of the screw with the top of the finger 25 and of the bottoms of the said holes 4, 4, with the under side of the finger, the neb is effectually clamped in place. Adjustment of the neb in the direction of the 50 length of the finger is readily accomplished 55 by turning the screw to loosen the engagement with the finger, sliding the neb in the one direction or the other as required, and then tightening up the screw again.

The parallel lateral extensions or wings 60 of the front and rear walls 3, 3, form vertical front and rear guides between which the end-journals of the top-rolls are received, and by which the top-rolls are restrained from loss of position either forwardly or rearwardly. The depending

tangs 5, 5, form end guides or stops by which the positions of the top-rolls longitudinally are controlled.

As a means of supporting the front end of the cap-bar finger 25, to sustain the said finger when it is turned down into its working position shown in Fig. 1, I form the back-wall 3 of the neb of the front top-roll with a rearwardly projecting foot 31, Figs. 1, 6, and 8, which is adapted to rest 75 upon the elevated rear portion 221 of the support 22 for the front bottom roll 23.

Nebs embodying the features of the present invention are designed to take the place in practice of the nebs previously mentioned herein and heretofore in general use, 80 consisting of blocks of steel machined to the required form. The invention remedies the drawbacks and disadvantages already referred to herein of such nebs, and provides 85 improved nebs of less cost, greater accuracy of shape and proportions, and more completely interchangeable upon the fingers upon which they are mounted than the solid machined nebs.

The accuracy and uniformity of shape which renders my nebs completely interchangeable is secured as a result of forming them of sheet metal stamped to shape. The saving in cost results from the fact that this 90 process of manufacture is far less expensive than the usual processes involving cutting and machining comparatively heavy pieces of metal, and also provides for a much higher rate of production. Less highly 100 trained and skilled workmen can be utilized for the manufacturing.

In the case of the production of nebs by cutting, machining, etc., bars and blocks of metal, various causes have resulted in inaccuracies in the grooved ends by which top-roll journals are controlled. These inaccuracies sometimes involve want of registration of the grooves at opposite ends of a neb, from which results an improper positioning of one of the associated top-rolls 110 upon the bottom rolls with which such top-rolls cooperate. That is to say, if the two grooves do not correspond with each other exactly in position, the longitudinal axis of one of the associated top-rolls may incline slightly in a direction from front to rear in relation to the axis of the bottom roll upon which it rests. The outcome of this is greater compression and wear of the intermediate portions of the top-roll bosses than of the ends of such bosses, so that sometimes after the top-rolls have been taken away from the cap-bars, as on the occasions on which cleaning of the machine is effected, it 125 follows from failure to re-apply the top-rolls to exactly the same nebs with which they were combined previous to the removal, a top-roll boss will rest by its relatively enlarged end-portions upon the corresponding 130

bottom roll and its reduced intermediate portion will fail to press and engage properly the sliver passing between the two rolls. My invention obviates this disadvantage 5 and deficiency, because as a result of the complete accuracy and uniformity of my improved nebs in form and proportions, they are all exactly alike when applied to the fingers 25. Hence, a top roll taken from 10 its place in connection with one pair of the nebs and applied in connection with another pair thereof will work in its new position exactly as it did in its prior position, because the accuracy of the form and 15 portions of the nebs, combined with accurate setting of the nebs upon the fingers 25, will enable each top roll to be placed and maintained in true working relations with the corresponding bottom roll by every pair of 20 nebs to which it may be applied, and hence when the top roll is shifted from one bottom roll to another by accident or design, no difference in the working relations will ensue.

25 What is claimed as the invention is,—

1. In cap-bar devices for roving and spinning frames, a top-roll neb composed of a single piece of sheet metal stamped or

pressed into shape and comprising a top-plate; front and rear walls having register- 30 ing holes therethrough to receive a cap-bar finger, the said walls having also lateral extensions or wings constituting vertical guides for top-roll journals; and depending tangs between such walls constituting end- 35 guides for said journals.

2. In cap-bar devices for roving and spinning frames, the combination with a neb according to claim 1, having a hole through its top-plate, of a nut occupying the enclosure 40 of said walls and tangs, between the top-plate and the top of a cap-bar finger, and a screw passing through the said hole and the nut and adapted to bear by its lower end against the top of the cap-bar finger. 45

3. A top-roll neb according to claim 1, having a rearwardly bent flange upon its rear wall constituting a foot adapted to support in working position a cap-bar finger and the nebs carried thereby. 50

In testimony whereof I affix my signature in presence of two witnesses.

GEORGE F. ALBRECHT.
